COMPASS

Francis E. Vaughan, Pasadena, Calif.

Application May 20, 1948, Serial No. 28,232

2 Claims. (Cl. 33—157)

1

My invention relates to new and useful improvements in compasses.

The object of my invention is to provide a compass having bifurcated legs with friction means for holding said bifurcated legs in desired angular relationships.

Another object of my invention is to provide a handle for manipulating said compass, means being provided whereby said handle is so constrained that its axis remains at, or near, the bisector of the angle between the legs as said legs are separated or brought together.

Another object of my invention is to provide a spacer for holding apart the upper portions of each of the bifurcated legs.

Another object of my invention is to provide a compass having legs bifurcated near the hinge in which a slidable erecting piece also serves as a spacer for holding apart the upper portions of each of the bifurcated legs.

Another object of my invention is to provide a compass in which the axis of symmetry of the slidable member is always at, or near, the bisector of the angle formed by the legs of the compass.

My invention has many other objects which will be apparent from a study of the following specifications read in connection with the accompanying drawings.

Referring to the drawings:

Fig. 1 is an upright front view of a compass embodying my invention;

Fig. 2 is an upright side view showing the bifurcated construction of the compass legs;

Fig. 3 is an upright front view of the erecting piece with the handle attached;

Fig. 4 is an upright side view of the erecting piece with the handle attached;

Fig. 5 is an enlarged fragmentary upright view of the hinge portion of the compass with a saucer-shaped member and its retaining screw removed to show structural relationships; and

Fig. 6 is a section taken along the line 6—6 in Fig. 1.

Referring to said drawings, the numeral 11 indicates a cylindrical hinge pin which carries the upper ends of the bifurcated legs 12 and 13, said legs being held against the hinge pin 11 by the saucer-shaped springs 14, which engage grooves 15 in the bifurcated leg 12 and grooves 16 in the bifurcated leg 13. As shown in the drawings, each of the bifurcated legs is constructed from two pieces fastened together adjacent their lower ends, but it is only necessary that the legs be bifurcated at their upper ends. The saucer-

2

shaped springs 14 are fastened to the hinge pin 11 by screws 17.

A slidable erecting piece 18 is positioned between the branches of the bifurcated legs 12 and 13, and carries a handle stem 19 to which is affixed the handle 20. The erecting piece 18 is provided with a slot 21 having parallel sides 22 and 23 fitting closely against the hinge pin 11.

The erecting piece 18 is operatively connected to each of the bifurcated legs 12 and 13. As an instance of this arrangement, the erecting piece 18 is provided with two pins 24, which are preferably, but not necessarily, firmly fitted to said erecting piece. These pins 24 extend from either side of the erecting piece 18 into slots 25 in at least one of the branches of each of the legs 12 and 13. These slots lie to either side of the hinge pin 11 and are elongated in directions approximately radial with respect to the center of said hinge pin. The upper and lower sides 26 and 27 of these slots 25 are parallel and fit closely against the pins 24.

As the lower ends of the legs are spread apart the legs 12 and 13 pivot about the hinge pin 11, thus causing the slots 25 to rise and carry with them the pins 24 and the slidable erecting piece 18, the slot 21 being provided to permit this rising of said erecting piece. Conversely, when the lower ends of the compass legs are brought together the erecting piece is lowered. Although the opening and closing of the legs causes the erecting piece 18 to be raised and lowered, it will be noted that the pins 24 prevent it from rotating in either direction about the hinge pin 11; it follows that the axis of the handle 20, produced downward between the legs 12 and 13, will continue to bisect the angle between said legs as it is increased or diminished by opening or closing the legs. Thus the handle remains in a convenient position above the legs and at the same time is maintained so rigidly with respect to them as to afford a convenient means for manipulating the entire device.

It will be noted that the friction between the slidable erecting piece 18 and the bifurcated legs 12 and 13 is of two kinds, friction due to the motion of rotation of said legs about the hinge pin 11 and friction due to the motion of the erecting piece 18 as the legs 12 and 13 are opened and closed. Another source of friction is at the points of contact between the grooves 15 and 16 in the branches of the compass legs and the saucer-shaped springs 14. When properly controlled, the friction from these various sources tends to hold the compass legs at any angle at which they

45

may be set, at the same time leaving them adjustable when sufficient force is applied to change this angle, and thus the spacing of the lower ends of the legs. In a broad sense, the total friction can be controlled by the pressure of the saucer-shaped springs 14 upon the branches of the legs 12 and 13. Since the screws 17 firmly press the springs 14 against the hinge pin 11, it follows that the pressure of these springs against the branches of the compass legs will be decreased as the effective length of the hinge pin 11 is increased and will be increased as the effective length of the hinge pin 11 is decreased. The effective length of the hinge pin can be changed by actually cutting the hinge pin itself, if it be too long, or by placing a thin washer between the saucer-shaped springs 14 and the hinge pin, if it be too short. The pressure of the saucer-shaped springs 14 against the branches of the compass legs 12 and 13 is also influenced, in some measure, by the thickness of said springs and the material of which they are constructed. Obviously, the thinner they are, the less the pressure, and, conversely, the thicker they are, the greater the pressure. It is clear that when the springs are sufficiently thin to yield appreciably when tightened against the hinge pin 11 by means of the screws 17, the adjustment by changing the effective length of the hinge pin 11 becomes less critical than when they are very stiff.

One of the advantages of my compass is that the hinge mechanism is adapted to use with bifurcated legs, a type of legs easily constructed and contributing toward making a compass of light weight.

Another advantage is that it is of simple sturdy construction, free of small parts, which are subject to wear and are easily lost, so commonly associated with the handle-erecting devices of compasses.

Another advantage is that it provides strong friction means for holding the legs at any desired angular setting, said friction means being easily adjusted and little subject to wear.

Another advantage is that the pins through the erecting piece can be made to extend from both sides into the branches of the legs, and, as a result, the forces applied to the pins and to the erecting piece, by opening and closing the legs, are symmetrical about two vertical planes of symmetry through the hinge of the compass, namely, about a vertical plane midway between the bifurcations of the compass legs and about another vertical plane perpendicular to the first plane and passing through the axis of the hinge pin. Because of this symmetry of forces about the hinge pin, there is no twisting action tending to develop lost motion or looseness in the hinge.

From the foregoing description taken in con-

nexion with the accompanying drawings, the uses, advantages, and operation of the compass of my invention will be readily understood by those skilled in the art to which the invention appertains. While I have described the form of my invention which I now consider to be the best embodiment thereof, I desire to have it understood that the compass shown is merely illustrative and that the invention is not to be limited to the details disclosed herein, but is to be accorded the full scope of the appended claims.

I claim:

1. A friction compass comprising a pair of non-overlapping legs each of which is bifurcated, a hinge pin, said legs having pivotal bearing surfaces abutting opposite sides of said hinge pin in facing relation, means for holding said legs in pivotal contact with said hinge pin, a spacing member slidably mounted between the branches of said legs, said slidably spacing member being provided with a slot having parallel sides closely fitting against said hinge pin and being so operatively connected to said legs that the axis of symmetry of said slidably spacing member substantially bisects the angle formed by said legs in any position, and means for holding the branches of said legs against said slidably spacing member in order to provide friction between said legs and said slidably spacing member.

2. A friction compass comprising a pair of non-overlapping legs each of which is bifurcated, a hinge pin, means for holding said legs in pivotal contact with said hinge pin, a spacing member slidably mounted between the branches of said legs, said slidably spacing member being provided with a handle and with two pins, each of which pins extends into holes in both branches of one of said compass legs, and means for frictionally holding the branches of said legs against said slidably spacing member.
